UNITED STATES PATENT OFFICE

2,558,565

CHART HOLDER

Louis E. Jensen and John Auer, Milwaukee, Wis.,
assignors to Universal Development Company,
Milwaukee, Wis.

Application December 13, 1948, Serial No. 65,036

4 Claims. (Cl. 40—84)

1

Our invention relates to chart holders and more particularly to an enclosure for encasing a plurality of charts or maps.

The object of our invention is to provide a means of suspending a plurality of charts within an enclosure.

Another object of our invention is to suspend various charts within an enclosure in a manner whereby they may be selected and exposed one at a time and only one chart at a time will be exposed for observation.

Still another object of our invention is to construct the device in a manner whereby the weight of the casing forming the enclosure insures and maintains a positive position of the exposed chart.

A further object of our invention is to provide a selector arrangement in the form of an index so that the proper chart is made available for exposition.

A still further object of our invention is to provide an enclosure for the protection of all charts encased therein when not in use.

It is manifest to any one familiar with the art that in a classroom or the like it is common practice to use charts for instruction purposes and quite frequently it is necessary and desirable to mount a plurality of charts at a particular location for the better observation by the pupils and the convenience of the instructor. The device described and claimed herein provides a single enclosure that encases a plurality of maps and charts, protecting them from dust or exposure and arranging them in a manner to permit selecting any one individual chart and placing it in an accessible position and retaining it in that position while it is exposed for use.

Other and further objects of our invention will become more apparent as the description proceeds when taken in conjunction with the drawings, in which

Figure 1 is a longitudinal cross sectional view of the entire assembled device.

Figure 2 is an end view of the outside of the enclosure showing the mounting bracket.

Figure 3 is an end view of one end of the chain and sprocket arrangement within the enclosure, and

Figure 4 is a similar view of the chain and sprocket arrangement in combination with the selector mechanism on the other end within the enclosure.

Similar characters of reference indicate corresponding parts throughout the several views and referring now to the same, the character 10 shows an outer shell which forms an enclosure,

5 this shell may be constructed of sheet metal or the like and is open at its lower end 11, and has its upper end radially formed as shown at 12.

There is an upper shaft 13 and a lower shaft 14 extending horizontally through the shell 10. These shafts 13 and 14 have sprockets shown as 15 attached near their ends. The upper shaft 13 is journaled in bearings shown as 16, supported by an attaching bracket 17 having outwardly extending members 18, and provided with engaging slots 19 which are open at their upper ends.

10 The shell 10 is provided with vertical slots 20 to permit up and down movement of the upper shaft 13. The lower shaft 14 is journaled in separate bearing shown as 21 supported by the side walls of the enclosure 10.

15 The sprockets 15 have five engaging slots shown as 22, however, any odd number of slots may be employed so that the sprockets may always be in alignment with one another in a manner whereby a slot 22 will always be at the top of the lower sprocket, when a pair of chains shown as 23 and having an even number of links 24 are employed. 20 The links 24 are constructed of pairs of plates arranged in staggered relation to one another, separated by pins or rollers 25 and these rollers 25 are of a size to fit the contour of the engaging slots 22 in the sprockets 15. The plates 24 on one chain 23 have round apertures 26 while the plates 24 on the other chain 23 have elongated apertures or slots 27. The apertures and slots 26 and 27 respectively, are in direct alignment with one another to accommodate a conventional type of spring roller onto which the charts or maps shown as 28 are mounted.

25 The shell 10 being supported by the lower shaft 14 permits the upper shaft 13 to slidably move within the vertical slots 20 in the shell 10 through 30 which the upper shaft 13 extends. The movement of the shaft 13 causes the raising and lowering of the shell 10 due to the revolving of the sprockets 15 which will then bring the distance between the shafts 13 and 14 either closer together or farther apart. They are shown to increase the distance between them when a chart 28 is at the extreme bottom of the lower sprocket 15, in which case a corresponding link 24 supporting a chart 28 is at the extreme top of the upper sprocket 15 as shown in Fig. 3. When an engaging slot 22 is at the top of the upper sprocket 15 and the bottom of the lower sprocket 15, the distance between the shafts 13 and 14 will decrease due to the weight of the shell 10.

35 There is an auxiliary shaft 29 journaled in a

single bearing 30, which is supported by one of the end walls of the shell 10, and a spur gear 31 is attached to the shaft 29. The spur gear 31 has teeth on its outer periphery which engage a pinion 32 which is mounted near one end of the bottom shaft 14, and a knob 33 is shown attached to the outer end of the shaft 14. This knob is employed to revolve the shaft 14. The auxiliary shaft 29 has an indicator hand 34 attached thereto and the outside end plate of the shell 10 has a plurality of digits or numerals 35 embossed or marked thereon. When the gears are properly calibrated, that is, when the gear 31 has sixty teeth, and there are twenty links shown as 24 in the chain 23, the pinion 32 on the shaft 14 when turned by the knob 33, must move the gear 31 a distance equivalent to three teeth on its outer periphery. Obviously, if there are twenty links in the chain there would be a provision for mounting twenty maps within the enclosure or shell 10 and the digits 35 would read from one to twenty inclusive, and every time the knob 33 is turned to bring the next link 24 into alignment with the opening 11 at the bottom of the shell 10 the indicator hand 34 would move to the next digit 35. In this manner the links could be numbered to correspond with the digits on a log or index of the charts, and the respective link mounting would provide selectivity in the relation of the indicator with the digits.

While we have shown a particular arrangement of the component parts constituting our device we are fully cognizant of the fact that many changes in the form and configuration of the component parts may be made without affecting their operativeness, and we reserve the right to make such changes as we deem necessary or convenient without departing from the spirit of our invention or the scope of the appended claims.

Having thus described our invention what we claim and desire to secure by Letters Patent in the United States is:

1. A device of the character described comprising in combination, an outer shell open at its lower end, an upper shaft extending longitudinally through said shell, a mounting bracket having a pair of outwardly extending arms, said upper shaft journaled within bearings disposed within said arms, the end plates of said shell provided with vertical slots for accommodating said upper shaft, a lower shaft extending longitudinally through said shell, a pair of bearings disposed within the lower portion of the end walls of said shell, said lower shaft journaled within said bearings, a pair of sprockets mounted onto said upper shaft, a pair of sprockets mounted onto said lower shaft, said sprockets equipped with an odd number of engaging slots on their outer periphery, a pair of link chains disposed over the periphery of said sprockets in engagement with said slots, a plurality of chart rollers, said chain links supporting said chart rollers, an auxiliary shaft, an auxiliary bearing mounted in one end wall of said shell, said auxiliary shaft journaled in said auxiliary bearing and projecting outward therefrom, a spur gear mounted on the said auxiliary shaft within said shell, an indicator mounted to the outwardly projecting end of said auxiliary shaft, digits disposed on the outer face of said end wall radially around the end of said auxiliary shaft, a pinion mounted to said lower shaft, said pinion in alignment and in engagement with said spur gear, and a knob attached to the outwardly extending end of said lower shaft for revolving

said shaft, thereby actuating said indicator for registration with said digits.

2. A device of the character described comprising in combination, a shell forming an enclosure provided with an elongated aperture at its lower end, an upper shaft extending longitudinally through said shell, a mounting bracket having a pair of outwardly extending arms, said upper shaft journaled within bearings disposed within the arms of said mounting bracket, the end plates of said shell provided with vertical slots for accommodating said upper shaft, a lower shaft extending longitudinally through said shell, a pair of bearings disposed within the lower portion of the end walls of said shell, said lower shaft journaled within said bearings, a pair of sprockets mounted on the said upper shaft, a pair of sprockets mounted on said lower shaft, said sprockets provided with engaging slots extending inward from the outer periphery of said sprockets, said slots being odd in number, a pair of link chains disposed over the periphery of said sprockets in engagement with said slots, a plurality of chart rollers, said chain links supporting said chart rollers, an auxiliary bearing supported by one end wall of said shell, an auxiliary shaft journaled within said auxiliary bearing and projecting outward therefrom, a spur gear mounted onto said auxiliary shaft within said shell, an indicator mounted to the outwardly projecting end of said auxiliary shaft, digits disposed on the outer surface of one of said end walls, said digits disposed radially around the end of said auxiliary shaft, a pinion mounted to one of said shafts within said enclosure, said pinion in alignment and engagement with said spur gear, and a wheel attached to the outwardly projecting end of the shaft supporting said pinion for revolving said shaft, thereby actuating said indicator in its relation with said digits.

3. A device of the character described comprising in combination, a shell forming an enclosure provided with an elongated aperture at its lower end, an upper shaft extending longitudinally through said shell, a mounting bracket having a pair of outwardly extending arms, said upper shaft journaled within bearings disposed within the arms on said mounting bracket, the end plate of said shell provided with vertical slots for accommodating said upper shaft, a lower shaft extending longitudinally through said shell, a pair of bearings disposed within the lower portion of the end walls of said shell, said lower shaft journaled within said bearings, sprockets mounted onto said upper and lower shafts within said shell near the end plates of said shell, said sprockets equipped with an odd number of engaging slots on their outer periphery, a pair of link chains disposed over the periphery of said sprockets in engagement with said slots, a plurality of chart rollers, said chain links supporting said chart rollers, an auxiliary bearing supported by one end wall of said shell near the lower end thereof, an auxiliary shaft journaled within said auxiliary bearing and projecting outward therefrom, a spur gear mounted on said auxiliary shaft within said shell, a pinion mounted on said lower shaft within said shell, for engagement with said bearing, an indicator mounted to the outwardly projecting end of said auxiliary shaft, numerals corresponding in number with the links on said chain disposed on the outer face of one of said end walls, said numerals arranged radially around the end of said auxiliary

ary shaft, said pinion on said lower shaft in direct alignment and engagement with said spur gear, and revolving means attached to the outwardly extending end of said lower shaft for revolving said shaft thereby actuating the indicator in its relation with the numerals on the outer face of the end wall.

4. A device of the character described comprising in combination, an outer shell open at its lower end, an upper shaft extending longitudinally through said shell, a mounting fixture extending longitudinally along the outer wall of said enclosures, said fixture having outwardly extending support arms, said upper shaft journaled within bearings disposed within said arms, the end plates of said shell provided with vertical slots for accommodating said upper shaft, a lower shaft extending longitudinally through said shell, a pair of bearings disposed within the lower portion of the end walls of said shell, said lower shaft journaled within said bearings, a pair of sprockets mounted onto said upper shaft, a pair of sprockets mounted onto said lower shaft, said sprockets equipped with an odd number of engaging slots on their outer peripheral surface, a pair of link chains engaging said sprockets, a plurality of chart rollers, said chain links supporting said chart rollers in longitudinal alignment with said enclosure, an auxiliary shaft, an auxiliary bearing mounted onto one end of

15
10
15

said shell, said auxiliary shaft journaled in said auxiliary bearing and projecting outward therefrom, a spur gear mounted onto said auxiliary shaft within said shell, an indicator mounted to the outwardly projecting end of said auxiliary shaft, outside of said shell, digits disposed in radial fashion round the outer end of said lower shaft on the outer face of the end wall of said enclosure, a pinion mounted to said lower shaft, said pinion in direct alignment and engagement with said spur gear, and revolving means attached to the outwardly extending end of said lower shaft for revolving said shaft thereby actuating said indicator in relation to said digits.
